ELECTRICAL DEVICE

BRIEF DESCRIPTION OF THE FIGURES

FIG. 1 is an illustration of an embodiment installed on an underside of kitchen cabinets;

FIG. 2 is an illustration of an embodiment of components for a lighting system;

FIG. 3 is an illustration of an embodiment of a display with kit components;

FIG. 4 is an illustration of an embodiment of an interconnect device;

FIG. 5 is an illustration of an embodiment of a portion of an interconnect device;

FIG. 6 is an illustration of an embodiment of an interconnect device in a disassembled view;

FIG. 7 is an illustration of an embodiment of an interconnect device in connection with a support and a strip of Light Emitting Diodes;

FIG. 8 is an illustration of an embodiment of an interconnect device in connection with a support and a strip of Light Emitting Diodes; and

FIG. 9 is an illustration of an embodiment of interconnect devices in connection with a support and a strip of Light Emitting Diodes; and

FIG. 10 is an illustration of an embodiment of wiring from an end of one lighting element to an end of another lighting element.

DETAILED DISCLOSURE OF EMBODIMENTS

Generally, FIG. 1 illustrates an embodiment in which an electrical device is usefully employed in a lighting system. The lighting system has lighting elements configured and installed on surfaces of kitchen cabinets. A kitchen implementation is used illustratively as the components are not limited use in any particular room or in an installation with cabinets.

Further, the lighting system elements need not be limited to the underside or be in a linear or planar orientation. In some embodiments, the lighting elements are implemented without a mechanical joint connecting them, using instead the wiring to connect the elements, which are in turn mounted to whatever surfaces are of interest. Thus, embodiments can be implemented in many geometries, including three-dimensionally with configurations of one or more lighting elements connected, if so desired, in series, parallel, or a combination thereof, and thence to an appropriate source(s) of power. Thus, in some configurations, multiple lighting elements can be configured in a "daisy chained" fashion with interconnecting wires between each element, while the source-proximate end of the daisy chain has wires connected to an appropriate power source, possibly through a dimming device. Additional illustrative configurations split into two or more single or daisy-chained strings of lighting elements at any point where interconnecting wires attach to an end of a lighting element. The lighting elements can therefore be combined in an angled orientation, for example, to match facets of cabinets, and/or be in orientations that are horizontal and/or vertical and/or there between, and combinations thereof.

In the prophetic illustration in FIG. 1, lighting elements 2(a-e) are shown mounted to kitchen cabinets 3(a-d) which have a variety of different widths, heights, and angles to meet various storage needs and room angles. Cabinets such as these come in industry-standard sizes of 3 inch linear increments, and the lighting elements 2(a-e) can have coop-

2

erating increments (see FIG. 2) if so desired, to fit according to these (or other) industry standard increments. That is, the lighting elements 2 can, but need not always, be made in lengths sized to approximately fit the variety of lengths (widths, heights, angles, etc.) for the cabinets or other standardized building components. A plurality of a lighting elements 2 can be configured collectively to fit in an installation that closely matches the width, angles, height, etc. of any, of the different kitchen cabinets 3.

10 Embodiments herein can utilize wiring 5 (see FIG. 10) from one lighting element 2 to another 2 to allow a single power supply 4 to provide power to a number of lighting elements 2, 3, 4, etc. The power supply can be Mean Well PLN-30-12 of Mean Well Taiwan, No.28, Wuquan 3rd Rd., Wugu Dist., New Taipei City 24891, Taiwan (R.O.C.)

Other embodiments can, if so desired, utilize more than one power supply 4 and sets of lighting elements 2 collectively specially adapted to be combined and positioned, for example, according to the variety of widths, lengths, etc. of the kitchen (bathroom, etc.) cabinets 3 and shelves, etc. so as to be affixed thereto. In other embodiments, the lighting elements 2 can be specially adapted to be combined and positioned to cooperate (e.g., electrically, illuminatively, structurally, etc.) with other apparatus for lighting, heating, steam generating, cooking, refrigerating, drying, ventilating, water supply and sanitary purposes.

FIG. 2 shows a variety of lighting elements (2a, etc.) of lengths differing by a scaling factor, e.g., 1 inch, 10 mm, or as desired, the elements in an array 7 from which a selection can be made to fit a desired application. To cooperate with consumer-selected elements 2 in the array 7, FIG. 2 shows a power supply 4 that accepts input power, e.g., from some source such as a residential electrical outlet, and converts this power to the appropriate voltage and current required to operate the lighting elements 2. Also illustrated is a dimmer module 6 which can be connected to throttle the electricity to the lighting element(s), e.g., between the output of the power supply 4 and the connections to the lighting element 2 and in some cases, other elements. The dimmer module 6 can, but need not always, be used in a configuration or operation for applications discussed herein, but may be used if so desired, e.g., mounted to the same or a different mounting surface as one or more of the lighting elements 2. Alternatively, the power supply 4 itself may have a capacity to perform the dimming function through internal circuitry.

FIG. 2 also shows that each lighting element 2 has at least one interconnect device 8c, but there may be multiple interconnect devices 8b, 8c, etc. at one end 14a, 14b, etc. As discussed below, each interconnect 8 has a set of at least two, but possibly more than two, terminals 22, each of the terminals 22 adjacent to a support 10 (see, e.g., FIG. 4). These interconnect devices 8 may be of the sort that allow a lighting element 2 to be connected to a power supply 4, if so desired, through a dimmer module 6, and/or to another lighting element 2, e.g., to connect lighting element 2a to another lighting element 2b and so forth, so as to form a daisy chain configuration. While the lighting elements 2 can be in contact with each other when mounted, in certain implementations, the elements 2 are devoid of a mechanical connection linking one lighting element 2 to another, other than the wiring 5 that is providing power. Therefore, in implementations devoid of a mechanical joint between the elements 2, other than the wiring 5, any combination (within the limits of the electricity) of the various lengths of lighting elements 2 can be interconnected in a configuration of

choice, in one dimension, two dimensions, or three dimensions of mounting surface, with elements in series, parallel, or both.

The array 7 is shown in FIG. 2 as having lengths organized into increasing or lengths, which can, if so desired, be presented in a display 9 illustrated in FIG. 3. The display 9 contains the array 7 as components of a kit with contents adapted to be positioned and surface-mounted respectively with the lighting elements 2 being devoid of a mechanical joint other than being connected by wiring 5 in the manner discussed herein, to share the power supply 4 to cooperate as a lighting system, wherein the lighting elements 2 are substantially identical except for length and the corresponding number of LEDs that fit with the length, in some cases, sharing a dimmer 6. In FIG. 3, dimmer 6 and wiring 5 are not shown, but a demonstrative installation 11 is, but need not always, be provided.

FIGS. 4 and 5 illustrate one of the many types of interconnect 8 devices that can be used. FIG. 4 is a side view and FIG. 5 is an end view, both showing an interconnect 8 body and handles 20(a, b) of the spring loaded cage connector terminal ports 22(a, b). The cage connector's handles 20, when depressed, open the connector terminal ports 22(a, b) so that interconnect wires of wiring 5 (not shown in FIG. 3) can be removed or inserted so as to be detachably attachable. The handles 20(a, b) and ports 22(a, b) are spring loaded so that when pressure on the handles 20(a, b) is released the connector ports close, based on spring tension, to establish secure mechanical and electrical contact with the interconnect wires.

Other kinds of interconnects can be used, depending on the implementation desired. Typically, though not necessarily, there is an electro-mechanical device for joining electrical circuits as an interface using a mechanical assembly. A terminal is a simple type of electrical connector that connects two or more wires to a single connection point. Wire nuts are another type of single point connector. Usually connectors utilize plugs (male-ended) and jacks (female-ended). The connection may be temporary or serve as a permanent electrical joint between two wires or devices. An adapter can be used to effectively bring together dissimilar connectors. Interconnects can include keying and/or locking mechanisms, and among the many possibilities for interconnects are terminal blocks, posts, crimp-on, insulation displacement, plug and socket, component and device, blade, ring and spade, hybrid, banana, barrier strip/spade lug, crimp, screw, and DIN connectors. Solder etc. is a less flexible connector.

Interconnect 8 is mounted on a support 10, which can be made of an electrical insulator, such as resin impregnated glass fiber, plastic, glass or other electrically, substantially non-conductive material. Depending on the implementation desired, the support 10 may be dimensioned to have a bottom length in the range of 20 mm to 40 mm. Support 10 can have a width based on the number of interconnects 8 supported (there can be more than one set of interconnects 8 at an end so as to have LED strips in parallel) and the dimensions of a housing 24. Support 10 can have a thickness of range of 2 mm to 4 mm, or such other dimensions that accommodate an LED strip 30 and provide stability with respect to a housing 24. LED strip 30 can be such as a model YL-5050 SMD-L60-WW of KINDOM OPTO-ELECTRONIC Co., Ltd Jiajun Industrial Park, Helong Road, Jiahe, Baiyun District, Guangzhou City, China.

In some embodiments, the support 10 can have a lesser thickness 12 in one direction (illustrated with a dashed line 18) defined by one end 14 with respect to another end 16 of

support 10. For example, the support 10 can be configured so that there is a plane 13 proximate to the interconnect 8 and another plane 15 distal to the interconnect 8 that is larger than the proximate plane 13, so that the different lengths 5 proscribe a sloping, tapering, or curving region, indicating a direction 18. In operation this feature facilitates transition of a flexible LED strip 30 from a housing 24, e.g., as illustrated in FIG. 8.

In implementations in which there are multiple interconnects 8a, 8b, the directions 18a, 18b of two of the supports 10a, 10b can be opposing directions, i.e., pointing toward each other with the LED strip between the interconnects 8a, 8b. In this orientation for the supports 10a, 10b, it is possible to have the terminals 22a of one of the interconnects 8a oriented with respect to the terminals 22b of the other of the interconnects 8b so that the terminals 22a, 22b point away from each other, while the supports 10a, 10b point toward each other.

Depending on the implementation, here in the teaching example in FIG. 4, the interconnect 8 assembly can include electrical extensions such as solder pads 45a, 45b, or other such manner of establishing an electrical connection between the interconnect 8 and a Light Emitting Diode strip 30.

In some but not all embodiments, it may be desirable to have circuitry 45a and 45b (FIG. 6) between the interconnect 8 and the strip 30, which includes the solder pads 45. And in some, but not all implementations of this type, interconnect 8 can have at least one conductive protrusion 52a, 52b, in electrical connection with terminal 22a, and at least one protrusion 53a, 53b in electrical connection with terminal 22b. The circuitry 48 can include at least one via 50a, 50b structured to accommodate the at least one conductive protrusion 52a, 52b, and at least one via 51a, 51b. The protrusions 52, 53 mate with vias (e.g., plated vias) 51, 52 so that the circuitry establishes electrical connections from the terminals 22a, 22b to the solder pads 45a, 45b. The protrusions 52, 53 can be soldered to plated vias 50, 51, with the extra set of protrusions 52b, 53b, and vias 50b and 51b used for redundancy and added support, of such is desired. If the plated vias 50 and/or protrusions 52 extend through the support 10, and if the housing 24 is electrically conductive, an insulator can be provided between the plated vias 50 and/or protrusions 52 and the housing 24.

FIGS. 7 and 8 illustrate LED strip 30 having at least one LED 31. LED strip 30 is operably connected to interconnect 8 by soldering LED strip 30's connections to solder pads 45a and 45b. Note that the circuitry 48 is structured to have the solder pads 45 positioned to mate with the soldering LED strip 30's connections. Alternatives to soldering such as spot welding, mechanical friction fit or other methodologies may also be used to establish the required electrical connections. Furthermore, the interconnect device 8, shown here as an assembly of an interconnect 8 and support 10 can be manufactured as a single assembly with the circuitry 45a and 45b, 48, 52 included as part of the integrated device.

FIG. 8 illustrates a side view of the interconnect 8 located with respect to the housing 24. The housing can be made of metal, plastic, wood, etc. In embodiments using the support 10, the support 10 can be mounted to the housing by way of adhesive, screw, bolt, weld, or other manner of securing. A housing 24 can have an end 14a adjacent to one of the interconnects 8a. As shown in FIG. 9, there is a second end 14b adjacent a second of the interconnects 8b, such that the interconnects 8 are oriented so that the directions 18a and 18b of the supports 10 are opposing directions, or said

another way, so that the directions **18a** and **18b** point to an opposite side of the support **10a** and **10b** than the terminals **22a** and **22b**.

In FIG. 10, a strip **30** of light-emitting diodes is operably connected intermediate the terminals **22** of the two interconnects **8a** and **8b** so as to power the diodes **30a** and **30b** etc. The strip **30** can be adhered or otherwise mounted to housing **24**. If so desired for one embodiment or another, LEDs **31** can be mounted on a rigid, semi-rigid or flexible circuit board to form a strip of LEDs **30**. The strip of LEDs **30** can be mounted on housing **24** adhesively or by mechanical mounting. The housing **24** and LED strip **30**, when combined with interconnect devices **8** at each end of the housing form, lighting element **2**. FIG. 9 also shows mounting adaptations **34a** and **34b**, in the illustrated embodiment, holes bored in housing **24**. Other mounting adaptations can be used, e.g., brackets, adhesive, spikes emerging from housing **24** to be driven into mounting surfaces, locations for fasteners overlapping the housing **24** to connect the housing **24** to a surface, etc.

In FIG. 10, lighting element **2a** is shown operably connected to lighting element **2b** by wiring **5** that is detachably attached to interconnects **8a** and **8c**, owing no mechanical joint between **2a** and **2b**. Power supply **4** (FIG. 2) can be connected to one of the set of terminals **22** of interconnect **8b** of the lighting element **2a** so as to drive the strip of light-emitting diodes **30a**, and if so desired, the wiring **5** can communicate power to strip **30b** via interconnects **8a** and **8c**. Embodiments that use multiple lighting elements **2** can be collectively integrated in such a way that when electric current is supplied to the interconnect device **8a** at one end of a lighting element **2**, a portion of that current is bussed through the strip **30a** to the interconnect device **8b** at the other end of that lighting element **2**. This allows multiple lighting elements **2** to be configured as a chain where current is supplied to one end of the chain, and then multiple lighting elements **2** are connected one to another by using sections of wiring **5** (such as an interconnecting cable). The lighting elements **2** are therefore structured to be selectively positioned with respect to each other when surface anchored by mounting adaptations on the housing **24**, e.g., holes for screws or nails, clips, etc. The lighting elements **2** can be in series, parallel, or a combination, with or without other lighting fixtures as may be desired, and having orientations in two or more dimensions, as may be desired, powered by the power supply **4** with no mechanical joint between the lighting elements **2** but for wiring **5** that is detachably attachable to one of the sets of the terminals **22** and to the other set of terminals **22**.

Embodiments, as noted above, can be modular. For example, one lighting element **2** can have a length and/or a number of the diodes that differs from another by a uniform scaling standard, e.g., one inch (10 mm, etc.) uniform difference between each lighting element **2**. A set of such modular lighting elements can be combined in the above-mentioned array **7**, for example, in a display **9** as shown in FIGS. 2 and 3.

The foregoing description of illustrated embodiments, including what is described in the Abstract are not intended to be exhaustive or to be limiting to the precise forms disclosed herein. While specific embodiments and examples are prophetically described herein for teaching-by-illustration purposes, various equivalent modifications should be recognized as possible within the spirit and scope of what is disclosed herein, as those skilled in the relevant art will recognize and appreciate. These modifications may be made

in light of the foregoing description of illustrated embodiments and are to be included within the true spirit and scope of the disclosure.

Accordingly, appreciation is requested for the robust range of possibilities flowing from the core teaching herein. More broadly, however, the terms and expressions which have been employed herein are used as terms of teaching and not of limitation, and there is no intention, in the use of such terms and expressions, of excluding equivalents of the features shown and described, or portions thereof, it being recognized that various modifications are possible within the scope of the embodiments contemplated and suggested herein. Further, various embodiments are as described and suggested herein. Although the disclosure herein has been described with reference to specific embodiments, the disclosures are intended to be illustrative and are not intended to be limiting. Various modifications and applications may occur to those skilled in the art without departing from the true spirit and scope defined herein.

Thus, although illustrative embodiments have been described in detail above, it is respectfully requested that appreciation be given for the modifications that can be made based on the exemplary embodiments, implementations, and variations, without materially departing from the novel teachings and advantages herein. As indicated herein, means-plus-function language is intended to cover the structures described herein as performing the recited function and not only structural equivalents, but also equivalent structures. Thus, although a nail and a screw may not be structural equivalents in that a nail employs a cylindrical surface to secure wooden parts together, whereas a screw employs a helical surface, in the environment fastening wooden parts, a nail and a screw may be equivalent structures.

I claim:

1. An apparatus including:
a first lighting element comprising:

two interconnects, each of the interconnects including a set of two or more terminals configured to provide attachably detachable wiring connections, each of the terminals located on a solder pad, the solder pads positioned to mate with connections of a strip of light-emitting diodes, the solder pads located on a support, each of the supports configured so that there is an interconnect-proximate plane and an interconnect-distal plane that is larger than the interconnect-proximate plane, so that different lengths of the planes indicate a direction, the supports mounted on a housing that contains the interconnects and the supports within ends of the housing, the housing including a hole adjacent each said end, the holes exterior to the supports and located to surface anchor the housing by the ends of the housing; and wherein the strip of light-emitting diodes is located in contact with the interconnect-proximate planes, between the solder pads and between walls of the housing, and is operably connected intermediate the sets of the terminals and substantially intermediate the directions so as to receive power for the strip of diodes from one said set of the terminals and communicate the power to another said set of the terminals.

2. The apparatus of claim 1, including:
a second lighting element comprising:

second two interconnects, each of the second interconnects including a second set of two or more second terminals configured to provide attachably detachable wiring connections, each of the second terminals located on a second solder pad, the second

solder pads positioned to mate with connections of a second strip of light-emitting diodes, the second solder pads located on a second support, each of the second supports configured so that there is an interconnect-proximate second plane and an interconnect-distal second plane that is larger than the interconnect-proximate second plane, so that different second lengths of the second planes indicate a second direction, the second supports mounted on a second housing that contains the second two interconnects and the second supports within ends of the second housing, the second housing including a hole adjacent each said second housing end and located to surface anchor the second housing by the second housing ends; wherein

the second strip of light-emitting diodes is located in contact with both of the second supports, between the second solder pads and between second walls of the second housing, and is operably connected intermediate the second sets of the second terminals and substantially intermediate the second directions so as to receive power for the second strip of diodes from one said second set of the second terminals and communicate the power to another said second set of the second terminals; wherein:

the lighting elements are made in different lengths, thereby defining a different distance between the holes of the first lighting element and the holes of the second lighting element, and structured to be selectively positioned with respect to each other when surface anchored with no mechanical joint between the lighting elements but for wiring.

3. The apparatus of claim 2, including:

a third lighting element comprising:

third two interconnects, each of the third interconnects including

a third set of two or more third terminals configured to provide attachably detachable wiring connections, each of the third two terminals located on a third solder pad, the third solder pads positioned to mate with connections of a third strip of light-emitting diodes, the third solder pads located on a third support, each of the third supports configured so that there is an interconnect-proximate third plane and an interconnect-distal third plane that is larger than the interconnect-proximate third plane, so that different lengths of the third planes prescribe a sloping, tapering, or curving region, indicating a third direction, the third supports mounted to a third housing that contains the third interconnects and the third supports within ends of the third housing, the third housing including a hole adjacent to each said third housing end and located to surface anchor the third housing; wherein

the third strip of light-emitting diodes is located in contact with both of the third supports, between the third solder pads and between third walls of the third housing, and is operably connected intermediate the third sets of the third terminals and the third directions as so to receive power for the third strip of diodes from one said third set of the third terminals and communicate the power to another said third set of the third terminals;

wherein:

the third lighting element is structured to be selectively positioned with respect to the first lighting

element and the second lighting element when surface anchored with no mechanical joint between the third lighting element and the first lighting element and the second lighting element but for wiring; and

each said first lighting element, said second lighting element, and said third lighting element made with a different length, thereby defining a different distance between the holes of the third lighting element and the distance between the holes of the second lighting element, and the distance between the holes of the first lighting element, and a different number of the diodes, and the different lengths are not the same by a scalar difference; and

a display of consumer-selectable, kit components, the display organizing a variety of lighting elements from which a consumer-selection can be made among an array of lighting elements made of different lengths including said first lighting element, said second lighting element, and said third element with the different lengths organized in an increasing or decreasing order.

4. The apparatus of claim 2, further comprising:
a power supply structured to change household electricity sufficient to drive more than one strip of light-emitting diodes; and

wiring from the power supply attached to the terminals of the one said set of the terminals, and wiring connecting the other of the set of terminals to one of the second set of terminals; and wherein the first lighting element and the second lighting element and the power supply, from a display of consumer-selectable kit components, the display organizing a variety of lighting elements from which a consumer-selection can be made among an array of lighting elements made of different lengths.

5. The apparatus of claim 2, further comprising:
a power supply structured to change household electricity sufficient to drive more than one strip of light-emitting diodes; and

wiring from the power supply attached to the terminals of the one said set of the terminals, and wiring connecting the other of the set of terminals to one of the second set of terminals; and wherein the first and the second lighting element and the power supply, from a display of consumer-selectable kit components, the display organizing a variety of lighting elements from which a consumer-selection can be made among an array of lighting elements made of different lengths.

6. The apparatus of claim 1, wherein: the strip of diodes is not coplanar with the housing and not coplanar with both of the planes.

7. The apparatus of claim 1, wherein:
each of the terminals is connected to an electrically conductive protrusion extending into a plated via that is connected to one of the solder pads, and ; wherein each of the sets of terminals comprise handles of spring-loaded cage connector terminal ports, such that the handles, when depressed, open the connector terminal ports so that wires can be removed or inserted, the handles and ports being spring loaded so that when pressure on the handles is released, the connector ports close, based on spring tension, to establish secure mechanical and electrical contact with wiring inserted therein.

8. The apparatus of claim 7, wherein the strip of diodes is in contact with the housing.

9

9. A method of making an apparatus, the method including:
 assembling a first lighting element by combining:
 two interconnects, each of the interconnects including
 a set of two or more terminals configured to provide
 attachably detachable wiring connections, each of
 the terminals located on a solder pad, the solder pads
 positioned to mate with connections of a strip of
 light-emitting diodes, the solder pads located on a
 support, each of the supports configured so that there
 is an interconnect-proximate plane and an interconnect-distal plane that is larger than the interconnect-
 proximate plane, so that different lengths of the
 planes indicate a direction, the supports mounted on
 a housing that contains the interconnects and the
 supports within ends of the housing, the housing
 including a hole adjacent each said end, the holes
 exterior to the supports and located to surface anchor
 the housing by the ends of the housing; and wherein
 the strip of light-emitting diodes is located in contact
 with the interconnect- proximate planes and the
 housing, between the solder pads and between walls
 of the housing, and is operably connected interme-

diate the sets of the terminals and substantially
 intermediate the directions so as to receive power for
 the strip of diodes from one said set of the terminals
 and communicate the power to another said set of the
 terminals.

10. The method of claim 9, further including providing,
 along with the lighting element, a power supply structured
 to change household electricity sufficient to drive more than
 one strip of light-emitting diodes.

11. The method of claim 9, wherein the attachably detach-
 able wiring connections are provided by each of the sets of
 terminals comprising handles of spring-loaded cage connec-
 tor terminal ports, such that the handles, when depressed,
 open the connector terminal ports so that wires can be
 removed or inserted, the handles and ports being spring
 loaded so that when pressure on the handles is released the
 connector ports close, based on spring tension, to establish
 secure mechanical and electrical contact with the wires
 inserted therein, and the first lighting element indicates +
 and - wiring connections.

12. A product produced by the process of claim 9.
